(57) **CLAIM**

The ornamental design for a turkey hammock, as shown and described.

DESCRIPTION

FIG. 1 is a top plan view of a turkey hammock showing our new design;

FIG. 2 is a rear elevational view thereof;

FIG. 3 is a front elevational view;

FIG. 4 is a bottom plan view thereof;

FIG. 5 is a left side elevational view thereof;

FIG. 6 is a right side elevational view thereof;

FIG. 7 is a left side elevational view of the turkey hammock as folded in half;

FIG. 8 is a front elevational view thereof; and,

FIG. 9 is a right side elevational view thereof.

The broken lines in the drawings depict unclaimed environmental structure.
